CLAIM

The ornamental design for a foldable leg support, as shown and described.

DESCRIPTION

FIG. 1 is a perspective view of a foldable leg support showing my new design in a folded configuration; FIG. 2 is a perspective view of the foldable leg support in an open configuration;

FIG. 3 is a perspective view of the foldable leg support in an open configuration during use thereof;

FIG. 4 is a view in front elevation of the foldable leg support in an open configuration;

FIG. 5 is a view in rear elevation of the foldable leg support in an open configuration;

FIG. 6 is a view in right side elevation of the foldable leg support in an open configuration;

FIG. 7 is a view in left side elevation of the foldable leg support of FIG. 1 in an open configuration in use thereof;

FIG. 8 is a top plan view of the foldable leg support in an open configuration; and,

FIG. 9 is a bottom plan view of the foldable leg support in an open configuration.

The broken lines in the drawings depict environmental subject matter and form no part of the claimed design.

1 Claim, 6 Drawing Sheets
